UNITED STATES PATENT OFFICE.

HARLAN S. NOYES, OF BROOKLYN, NEW YORK.

DESIGN FOR A WATCH-CASE OR LOCKET.

SPECIFICATION forming part of Design No. 18,532, dated August 14, 1888.

Application filed May 18, 1888. Serial No. 274,329. Term of patent 14 years.

To all whom it may concern:

Be it known that I, HARLAN S. NOYES, a citizen of the United States, residing at Brooklyn, in the State of New York, have invented and produced a new and original Design for Watch-Cases or Lockets, of which the following is a specification, reference being had to the accompanying drawing, forming part thereof.

10 The drawing is a face or front view of the case, in which A is the lid or back, and B the rim or center, which is made in shape of a keystone extending beyond the exterior of the back or lid, and is provided on the top with

15 a truncated piece or projection, as is often seen in keystones. The stem is usually attached at the center of the truncated piece, as shown,

although it may be omitted or attached elsewhere, as it forms no part of my design.

The leading features of this my design consist of the circular part A and the part B in the form of a keystone having a truncated piece on the top thereof.

What I claim as new, and desire to secure by Letters Patent, is—

The design for a watch-case or locket herein shown and described, consisting of a case the outline whereof is in the form of a keystone having a truncated piece at the top, substantially as specified.

HARLAN S. NOYES.
